United States Patent Office

Des. 198,745
Patented July 28, 1964

198,745

CHAIR

Ralph E. Lambrecht, Waukegan, Ill., assignor to Outboard Marine Corporation, Waukegan, Ill., a corporation of Delaware

Filed May 1, 1962, Ser. No. 69,924

Term of patent 14 years

(Cl. D15—1)

FIGURE 1 is a perspective view showing the top, front, and one side of a chair incorporating my new design;
FIGURE 2 is a top plan view of the chair shown in FIGURE 1;

FIGURE 3 is a side elevational view of the chair shown in FIGURE 1; and

FIGURE 4 is a bottom view of the chair shown in FIGURE 1;

FIGURE 5 is a rear elevational view of the chair shown in FIGURE 1.

The dominant features of my design are shown in FIGURES 1 through 5 in full lines, and the immaterial or unimportant parts of my design reside in those portions shown in full lines in the drawing.

I claim:

The ornamental design for a chair, as shown and described.
